INSECTICIDE VAPORIZER

Francis C. Leitch, Lawrence M. Kissner, and James E. Leitch, Owosso, and Clifford C. Chapel, Flint, Mich., assignors to De-Bug-er, Inc., Owosso, Mich.

Application February 10, 1951, Serial No. 14,172

Term of patent 7 years

(Cl. D31—3)

To all whom it may concern:

Be it known that we, Clifford C. Chapel, Lawrence M. Kissner, James E. Leitch, and Francis C. Leitch, all citizens of the United States of America, said Clifford C. Chapel residing at Flint, in the county of Genesee and State of Michigan, and Lawrence M. Kissner, James E. Leitch, and Francis C. Leitch, all residing at Owosso, in the county of Shiawassee and State of Michigan, have invented a new, original, and ornamental Design for an Insecticide Vaporizer, of which the following is a specification, reference being had to the accompanying drawing, forming part thereof.

In the drawing:

Fig. 1 is a perspective view of an insecticide vaporizer, showing our new design; and

Fig. 2 is an edge elevational view thereof.

We claim:

The ornamental design for an insecticide vaporizer, as shown.

FRANCIS C. LEITCH.
LAWRENCE M. KISSNER.
JAMES E. LEITCH.
CLIFFORD C. CHAPEL.
